GRINDING MACHINE

Earle L. Harley, Brooklyn, N. Y.

Application December 29, 1950, Serial No. 203,313

3 Claims. (Cl. 51—105)

1

My invention relates to grinding or abrading machines and, more particularly, to a machine for grinding surfaces such as either surface of printing plates produced in a hydraulic press and composed of rubber, plastic or other suitable material, or for re-surfacing items such as offset blankets.

The object of my invention is to produce a grinding machine in which the cylinder bearing the article to be ground is adjustable toward and away from the grinding roller, the feed, rate of grind, and speed of rotation of the cylinder being automatically controlled.

Another object is to produce a grinding machine of the character described in which the adjustable cylinder is automatically stopped when the predetermined amount of grinding has been accomplished.

Another object is to produce a machine of the character described in which the grinding surface is maintained in an even condition by means of an automatic tension device associated with the strip of abrasive material with which the grinding roller is furnished.

Another object is to produce a machine of the character described in which the surface to be ground or abraded is adjustable with respect to the abrasive roller during rotation of the cylinder supporting said surface.

A further object is to provide a machine of this type in which the above and other objects as will hereinafter be described may be attained.

A practical embodiment of my invention is represented in the accompanying drawings in which:

Fig. 1 represents an end elevation of a machine constructed according to my invention.

Fig. 2 represents a front elevation, partly broken away, of the form shown in Fig. 1.

Fig. 3 represents a vertical longitudinal section taken on the line III—III of Fig. 1 looking in the direction of the arrows.

Fig. 4 represents a partial detail section taken on the line IV—IV of Fig. 3 looking in the direction of the arrows.

Fig. 5 represents a detail showing contact of the grinding roller with the object to be ground.

Fig. 6 shows a view similar to Fig. 5 in transverse vertical section.

Fig. 7 represents a detail showing the arm attached to the eccentric shaft, the cam actuating said arm, the drive for the cam and the switch actuated by the arm, and

Fig. 8 represents a wiring diagram laid out in approximately the same physical location that the parts occupy in the machine.

2

Broadly my invention comprises a grinding machine including means for maintaining the grinding surface under tension and other interrelated means for controlling the grinding operation through automatic control of the cylinder supporting the article to be ground together with the drive for said cylinder.

Referring to the accompanying drawings, the frame of the machine is shown as comprising a lower casting 1 supporting an upper casting 2 which is bolted thereon or otherwise secured thereto. Supported in the lower part of casting 1 are two motors 3 and 4 of different horsepower which provide a drive for various elements of the machine as will hereinafter be described. Situated on the same level as the motors is a reduction gear 5 which is in turn connected to a reduction gear 6 affixed to the upper casting 2. The said upper casting is provided with the usual pillow blocks 7, 8 which are adapted to support the eccentric ends 9' of the shaft 9. Rotatably supported on the shaft 9 are interior ball bearings 11, 12 which are secured in opposite ends of cylinder 10. Also affixed to the end of cylinder 10 is a sprocket 13 adapted to receive the chain 14, which is driven by its connection with the sprocket 15 mounted on the shaft 16, which is the output shaft of the lower reduction gear.

The supporting cylinder 10 is provided with scribe marks 17, 18 adjacent its ends in order to delimit the surface to which the surface to be ground may be affixed. These surfaces may be printing plates 19, 20 of various materials or offset blankets. As shown in Fig. 2 rubber printing plates are affixed so that their edges are not parallel to the cylinder axes by placing masking tape 21, 22 across the leading edges, the tail of the plate being held to the cylinder by a plurality of tabs denoted collectively by 23.

Mounted in parallelism with the longitudinal axis of the cylinder 10 is a grinding roller 24 provided with an abrasive surface 25 held thereon under tension as described in my copending application Serial No. 203,314 filed December 29, 1950, now Patent No. 2,630,657, dated March 10, 1953. This roller 24 is mounted on a shaft 26 formed integral therewith and shaped at 27 to accommodate a belt 28 driven from the larger motor 4 hereinabove described. The ends of shaft 26 of the roller 24 are suitably journaled in mountings 29 and 30 bolted or otherwise secured to the top of casting 2 as shown in Figs. 1 and 2. Rotatably mounted beneath and in contact with the outer surface of cylinder 10 is the rotary brush 31 which is driven from the opposite end of the larger motor 4 by which the roller 24

is driven through its belt 32. It will be noted that the brush 31 and roller 24 rotate in the same direction as the cylinder 10 and both the brush and roller are rotated at a constant and the same speed. Beneath the brush 31 I provide a receptacle 33, having three vertical sides uprising from the bottom, to receive the ground material and permit its removal therefrom. This receptacle may be supported in any well known or approved manner and is not ordinarily removable.

Attached to the outer end of casting 2 is a graduated scale 34 (shown in Fig. 1) and having a pointer 35 adapted to co-act therewith, said pointer being secured to a knob 36 carried by one of the eccentric ends 9' of shaft 9.

Also connected to an eccentric end 9' of the shaft 9 is an arm 37 having a split end 38 which enables it to be clamped to the shaft 9 by means of a set screw 39. This arm extends laterally and terminates in a roller 40 which is held in contact with the peripheral surface of an S shaped cam 41 by means of a spring 42 connected to the said arm at one end and to the casting 1 at the other end by means of a rod or other connection 43. The arm 37 has an elbow 44 adapted to contact and actuate a switch 45 as will be described below. Cam 41 is driven through its connection 53 with the output shaft 46 of the upper reduction gear, which in turn is driven from the lower reduction gear by driving means 47, which gear is driven from the smaller motor 3 by a chain and sprocket connection.

At the front of the machine are provided switches 48 and 49, switch 48 being connected with switch 45, as shown in Fig. 8, and switch 49 being connected with the larger motor 4.

Switch 49 controls the operation of the motor 4 which is 3 phase, 60 cycle 220 volt by manual operation of said switch.

The operation of the single motor 3 is controlled by automatic switch 45 and manual switch 48. When the automatic switch 45 is in position A switch 48 is turned to position A' to start motor #3. When the grinding cycle has been completed the arm 37 having an elbow 44 activates automatic switch 45 moving it into position B, thus, stopping the motor 3. To start motor 3 again, it is necessary to manually operate switch 48 by moving it to position B'.

The operation of the machine is as follows:

Plates 19 and 20 are affixed to cylinder 10 with their backs exposed, as shown in Fig. 2, by means of tapes 21, 22 and tabs 23. The larger motor 4 is started by manually throwing switch 49, which will rotate the grinding roller 24 and the brush 31 at the same speed through means previously described. Arm 37 is adjusted on shaft 9 with respect to cam 41 so that when the arm roller 40 is in the depressed portion of the cam, the pointer 35 will show the thickness to which the plate will be ground. At this point the switch 48 is actuated, which starts the smaller motor 3 and rotates the cylinder 10 carrying the plates 19 and 20 as well as rotating the S shaped cam 41. As the cam turns it will be seen that the roller 40 riding on the cam surface will raise the arm 37, which is clamped to shaft 9, and will advance the eccentric bearing carrying cylinder 10 on shaft 9 toward the grinding roller 24. It will thus be seen that the surface to be ground is slowly advanced toward the rotating grinding surface 25 as the cylinder 10 and the cam 41 are rotated. The cam 41 is so shaped that during the latter several revolutions of cylinder 10 prior to the completion of the grinding operation the roller 40 will ride on a "flat" on the cam 41. This

insures the completion of the grinding operation to the desired degree. When the roller reaches the end of this flat on the cam due to the continuous rotation of the latter, the arm 37 will be pulled down into the low portion of the cam 41 by means of spring 42 mounted as described above. This action of the arm 37 causes its elbow 44 to contact and actuate the switch 45. The latter being a double pole, double throw switch and being inter-connected with switch 48 operates to stop the smaller motor 3 which, as described above, serves to drive cylinder 10 and the cam 41. The action of the arm will also serve to re-set the eccentric bearing to its starting position. The plates 19 and 20 having been ground to the desired degree may now be removed from the cylinder 10 and trimmed for use in a printing press. To stop the grinding roller 24 and the brush 31 it is necessary to throw the switch 49 manually.

Removable covers 50 and 51 may be provided for the front and back of the machine if desired and they are secured in any well known or approved manner to the castings 1 and 2.

It will be understood that there are two sources of current supply, one for each motor, the larger being a three phase motor, as shown in Fig. 8.

It will also be understood that printing surfaces of printing plates may also be refinished in this machine by adhering them with the printing surface outward so that it may be contacted by the grinding roller surface.

Since it is evident that various changes may be resorted to in the construction, form and arrangement of the several parts without departing from the spirit and scope of my invention, I do not intend to be limited to the particular embodiment herein shown and described except as set forth in the claims.

What I claim is:

1. A machine of the character described for grinding an object comprising, a rotatable grinding roller, a rotatable support for the object to be ground, a gauge attached to said support for setting the grinding depth, means for rotating the roller at one speed, other means for rotating the support at a lesser speed, eccentric bearings in said support, an arm connected to said bearings, a switch controlling said support rotating means, a projection on said arm in proximity to the switch, a roller on said arm, a cam engaging said roller, cam driving means, and a common frame for supporting said elements, the elements being so constructed and arranged that when the gauged depth has been attained the arm projection moves and actuates the switch to stop the support rotating and the cam driving means.

2. A machine of the character described for grinding an object comprising, a rotatable grinding roller, a rotatable support for the object to be ground, a gauge attached to said support for setting the grinding depth, means for rotating the roller at one speed, other means for rotating the support at a lesser speed, eccentric bearings in said support, an arm connected to said bearings, a switch controlling said support rotating means, a projection on said arm in proximity to the switch, a roller on said arm, and an S-shaped cam engaging said roller, means for driving said cam, a common support for all of said elements, the parts being so constructed and arranged that when the gauged depth has been attained, the arm projection actuates the switch to stop the rotating means for the support and said cam, the support being rotated for a period subsequent to

the attainment of the grinding depth as determined by the shape of the cam surface engaging said roller before the roller arm projection actuates the switch to stop the support rotating means.

3. A machine of the character described for grinding an object comprising a rotatable grinding roller, a rotatable support for the object to be ground, means for rotating the roller, other means for rotating the support, and a third 10 means for bringing the support into operative relationship with a roller surface plus interconnected controls for the support rotating means operable by a switch for controlling the support rotating means and including a driven cam, a 15 roller riding thereon and an arm carrying said roller, said arm being connected to the support and carrying an element thereon between its ends

for actuating said controlling switch when the grinding operation has been completed.
